UNITED STATES PATENT OFFICE.

LOUIS LEMKUHL, OF BALTIMORE, MARYLAND.

ADJUSTABLE SHADE-HANGER.

1,087,386.

Specification of Letters Patent.

Patented Feb. 17, 1914.

Application filed April 24, 1913. Serial No. 763,359.

To all whom it may concern:

Be it known that I, LOUIS LEMKUHL, a citizen of the United States, residing at Baltimore city, in the State of Maryland, have invented certain new and useful Improvements in Adjustable Shade-Hangers; and I do declare the following to be a full, clear, and exact description of the invention, such as will enable others skilled in the art 10 to which it appertains to make and use the same.

This invention relates to shades, and more especially to the vertically adjustable hangers for carrying the same; and the object 15 of the invention is to produce a hanger of this character having its upper section hinged so that the shade roller may be thrown forward or inward out of the window frame when desired. Further objects 20 will appear from the following specification, and the invention is illustrated in the accompanying drawings wherein—

Figure 1 is a front elevation of this device applied to a window; Fig. 2 is a section 25 on the line 2—3 of Fig. 1; and Fig. 3 is a similar section with the upper section of the hanger tipped forward or inward. Fig. 4 is an enlarged front elevation of the lower portion of the hanger, one end being in central vertical section; and Fig. 5 is a similar 30 view of the left end of the device shown in Fig. 4, with the parts in a different position. Fig. 6 is a horizontal section on the line 6—6 of Fig. 4. Fig. 7 is an enlarged detail, 35 giving an elevation of one of the side rails of the frame; and Figs. 8 and 9 are sectional views on the line 8—9 of Fig. 7 showing the parts in slightly different positions. Figs. 10 and 11 are still further enlarged-sections 40 on the lines 10—10 and 11—11 respectively of Fig. 7.

In the drawings is shown a window frame W, and an ordinary shade S mounted on a spring roller R which is journaled in brackets B—these brackets being fixed in a frame which moves up and down in the window frame and forms a part of the present invention. Said frame comprises two upright side bars 1 rigidly connected near but not 45 quite at their lower ends by a lower cross rail 2, and the upper sections or portions 3 of said side bars are rigidly connected at their upper extremities by an upper cross rail 4 and carry the brackets B just beneath 50 this rail. The entire frame is movable vertically within the window frame W, and the

sides of the latter carry rack bars 5 whose inner edges are provided as shown with ratchet teeth while their bodies form dove-tailed ribs engaged by upright grooves 6 in 55 the outer edges of the lower portions of the side bars 1. Said rack bars may extend down to the window sill, but at their upper ends they terminate at points 7 which are short of the window cap by a distance equal 60 to the length of the upper portions 3 of the side bars, for a purpose yet to appear. Each side bar 1 near its lower end is recessed as at 8, and pivoted at 9 in the recess is an L-shaped dog 10 having a beveled head 11 at 65 its upper end adapted to engage the ratchet teeth, while its horizontal arm is thrown normally upward by a spring 12. A movable rail 13 extends across the frame just above the lower rail 2 and its extremities 70 project into the recesses 8 and over the inner ends of said dogs, its own ends being provided with upright slots 14 engaging pins 15 so that it may not become displaced. When the operator grasps the rails 13 and 75 20 in his hand and presses them together he depresses the movable rail with respect to the lower rail and the entire frame and the ends of the former trip the dog so that their heads 11 disengage the rack bars and 80 the entire frame can be raised or lowered—in fact this frame can be raised by passing the hand under the lower rail and lifting on it, although this follows only from making the teeth in the rack bars ratchet shaped 85 and the heads 11 of the dog beveled on their upper sides as shown, and to this construction I do not wish to be strictly limited. With a structure as thus far described, it 90 is obvious that the entire frame and with it 95 the shade roller and shade may be adjusted vertically within the window frame as desired.

A feature of my invention consists in hinging the upper portions 3 of the side bars to the lower portions 1 thereof so that the upper portion of the frame can be tilted forward or into the room as indicated in Fig. 3. Referring now more particularly to Figs. 7, 8, and 9, the upper end 100 of each side bar 1 is provided with a socket 20 whose rear side rises higher than its front side and constitutes a tongue 21 which is dove-tailed in cross section as seen in Fig. 10; and across this socket extends a 110 pin 22. The lower end of the upper section 3 is provided with a tenon 24 of a shape

and size adapting it to fit said socket 20 when the parts stand in alinement as seen in Fig. 8, and through this tenon is an upright slot 25 movable on the pin 22. The 5 shoulder at the rear of said tongue is provided with a notch 26 which is dove-tailed in cross section and which at this time engages the dove-tail tongue 21. Finally, the lower end of the tenon is beveled as shown 10 at 27. Ordinarily the parts stand as seen in Figs. 7 and 8, and the upper portions 3 of the frame bars are reciprocated with the lower portion. When, however, the frame is pushed upward to its limit so that the 15 hinges between the upper and lower portions of its side bars come opposite to or above the points 7 where the rack bars terminate, it is possible for the operator to grasp the upper cross rail 4, lift the entire 20 upper portion of the frame until the tenons 24 slide upward within the sockets 20 and the slots 25 slide upward on the pins 22, and then bear this upper portion of the frame forward to the position shown in Figs. 3 and 25 9 so that the beveled lower end 27 of each tongue strikes the rear wall of the socket 20 and the shade roller R is carried forward out of its usual position. This adaptability 30 of my device is useful where it is desired to admit air to the room above the shade, and yet not admit too much light or any sunlight at this point. In any and all positions of this hanger it is possible to raise and lower the shade S as usual, but when the 35 upper portion of the frame is set inward as shown in Fig. 3 I would preferably pass the shade behind the lower rails 2 and 13 thereof which carry it inward toward the window sashes.

40 The parts of this device are of any preferred materials, and I do not wish to be limited to details except as set forth in the following claims:

What is claimed as new is:

45 1. An adjustable shade hanger made in two sections hingedly connected with each other, and means for adjustably supporting the lower section in a window frame; combined with means for setting the upper section at an angle to the lower section, for the purpose set forth.

50 2. An adjustable shade hanger made in two sections hingedly connected with each other, and means for guiding and supporting the lower section in a window frame; combined with means for setting the upper section at a slight angle to the lower section when the latter is raised.

55 3. In an adjustable shade hanger, the combination with the window frame having upright rack bars in its inner faces; of a frame whose side bars are grooved to engage said rack bars, a shade roller mounted in the upper portion of said frame, spring-actu-

ated dogs movably engaging said rack bars, 65 and a movable rail adjacent the lower cross rail of the frame and having its extremities engaging said dogs, for the purpose set forth.

4. In an adjustable shade hanger, the 70 combination with the window frame having upright ratchet bars in its inner faces extending to points near its upper end; of a frame whereof the lower portions of its side bars are grooved to slidably engage said 75 ratchet bars and the upper portions thereof are hingedly connected with said lower portions, the latter having recesses near their lower ends, an L-shaped dog pivoted at its angle in each recess and having a head 80 adapted to engage a rack bar and beveled on its upper side, a spring normally raising the horizontal arm of said dog and throwing the head into engagement with the teeth of the ratchet bar, a movable rail extending 85 across the lower portion of the frame and its ends passing into said recesses and lying over the horizontal arms of said dogs, this rail having upright slots within said recesses, and pins through the recesses loosely 90 engaging said slots, the whole constructed for operation substantially as described.

5. An adjustable shade hanger including a frame whereof each side bar is in upper and lower sections, the latter having a socket at 95 its upper end and the rear wall of said socket being projected upward into a tongue of dove-tailed cross section, and the lower end of the upper section having a tenon adapted to engage said socket and a notch at the rear end of the tenon adapted 100 to engage said tongue when the parts stand in alinement.

6. An adjustable shade hanger including a frame whereof each side bar is in upper and lower sections, the latter having a socket at 105 its upper end and the rear wall of said socket being projected upward into a tongue of dove-tailed cross section, a pin extending 110 transversely across this socket, and the lower end of the upper section having a tenon adapted to engage said socket and the tenon having an upright slot loosely engaging said pin, the shoulder at the rear of said tenon being adapted to engage said tongue when 115 the parts stand in alinement.

7. An adjustable shade hanger including a frame whereof each side bar is in upper and lower sections, the latter having a socket at 120 its upper end and the rear wall of said socket being projected upward into a tongue of dove-tailed cross section, a pin extending transversely across this socket, and the lower end of the upper section having a tenon adapted to engage said socket and the tenon having an upright slot loosely engaging 125 said pin and the lower extremity of said tenon being beveled, the shoulder at the rear

side of said tenon being adapted to engage said tongue when the parts stand in alinement.

8. An adjustable shade hanger including a frame whereof each side bar is in upper and lower sections, the latter having a socket at its upper end, a pin extending transversely across this socket, and the lower end of the upper section having a tenon adapted 10 to engage said socket and provided with an upright slot loosely engaging said pin, the lower end of said tenon being beveled, for the purpose set forth.

9. In an adjustable shade hanger, the 15 combination with the window frame having upright ratchet bars in its inner faces extending to points near its upper end; of a frame whereof the lower portions of its side bars are grooved to slidably engage said

ratchet bars and the upper portions thereof 20 are hingedly connected with said lower portions, the latter having recesses near their lower ends, an L-shaped dog pivoted at its angle in each recess and having a head adapted to engage a rack bar and beveled on 25 its upper side, a spring normally raising the horizontal arm of said dog and throwing the head into engagement with the teeth of the ratchet bar, and means for depressing said arm, the whole constructed for operation substantially as described.

In testimony whereof I have hereunto set my hand in presence of two subscribing witnesses.

LOUIS LEMKUHL.
